UNITED STATES PATENT OFFICE.

SAMUEL SEGAL, OF NEW YORK, N. Y., ASSIGNOR TO SEGAL LOCK & HARDWARE CO. INC., OF NEW YORK, N. Y., A CORPORATION OF NEW YORK.

LOCK.

Application filed December 31, 1926. Serial No. 158,135.

It is an object of the invention to provide a lock of improved construction in which a forcible retraction of the bolt or bolts from within the lock keeper will be prevented.

5 It is a further object to provide a device of this character in which the bolt or bolts will be readily projectable within a keeper or retractable therefrom when properly operated.

10 Another object is that of providing a lock embodying a number of parts, the construction of each of which will be individually simple and which may be readily assembled by comparatively unskilled labor to provide 15 an improved lock operating over long periods of time with freedom from mechanical difficulty.

For a fuller understanding of the nature and objects of the invention reference should 20 be had to the following detailed description taken in connection with the accompanying drawings in which:

Figure 1 is a partly sectional side elevation of a lock embodying the improved construction of the present invention and showing the parts thereof in retracted position;

Fig. 2 is a similar view, showing the parts partially projected;

Fig. 3 is a view corresponding to Figs. 1 30 and 2, with the rear portion of the casing broken away, and showing the parts wholly projected;

Fig. 4 is a fragmentary face view of the interior of the lock case;

35 Fig. 5 is an enlarged sectional view taken along the lines 5—5 of Fig. 1; and

Fig. 6 is a transverse sectional view taken along the lines 6—6 of Fig. 1.

In these several views the numeral 10 indicates a case which may be formed of any suitable material, and within which a dead-bolt 11 is slidably mounted; this bolt being formed with bores 12 (in the present exemplification two in number) extending in its direction of travel, and each of these bores mounting rotatable bolts 13 having oblong heads 14.

50 In order to effect a projection and retraction of this bolt assembly a carrier is secured to and extends from the rear edge of the dead-bolt 11, this carrier in the present instance including a T-shaped plate 15 riding upon guides 16 having the outer ends of its arms flanged inwardly as at 17. As has been best shown in Figs. 2, 3 and 5, 55 the plate 15 is formed with a key-hole slot 17,

within which a pin 18 rides, this pin extending between the arms of a fork-shaped crank 19 secured to the rotatable shaft 20 mounted by the case 10 and actuated by a knob 21. Thus, when the crank is oscillated the pin 18, which is connected with the plate in a manner hereinafter described, will cause this plate and the bolt assembly to be moved outwardly or retracted within the lock case.

The rear ends of the shafts 13 providing the rotatable bolts are each transversely bored and receive a pin 22, the length of which is in excess of the diameter of the shaft with which it is associated. The rear end of the dead-bolt 11 is formed with grooves or, as shown, slots 23, disposed at a tangent to the direction of travel of the bolt assembly, and the ends of the pins 22 ride within these slots. The lock case 10 carries rails 24, which lie at a point adjacent the path of travel of the bolts 13, and the pins 22 are of such a length that their inner ends lie adjacent the contact edges of the rails 24 when the bolt assembly is retracted; these edges being preferably beveled. Thus, a rotation of the shafts providing the rotatable bolts is normally prevented, and, as a consequence, when the bolt assembly is projected, all elements thereof will move outwardly as a unit. Abutments 25 conveniently form a part of the lock case and are disposed in positions spaced from the outer edges 26 of the rail members 24 and in line with the path of travel of the pins. As a consequence, it will be understood that, upon the bolt assembly being projected to a point 90 at which the pins 22 engage the abutments 25, their further movement as a unit with the dead-bolt will be prevented and they will remain in their projected position during the continued forward movement of the latter. 95 Incident to the tangentially-extending slots 23, the side edges of which engage the pins 22, this movement of the dead-bolt with respect to the shafts 13 will result in a rotation of the latter, so that the heads 14 carried by the shafts will be rocked.

Again considering the sequence of operations with the parts in the position shown in Fig. 1, the heads 14 in the present embodiment of the invention will be disposed longitudinally of the end edge of the lock case and recessed therein. A thrust upon the extension-plate 15 will result in the bolt assembly moving forward as one unit to the position shown in Fig. 2, the shafts 13 remaining 100 105 110

fixed with respect to the dead-bolt and with the heads extending materially beyond the leading edge of the latter, and during such movement these heads will enter a keeper (not shown) which has an inwardly-extending flange or flanges. A continued thrust upon the dead-bolt will cause the latter to move outwardly to a position beyond the forward edge of the lock case, and the shafts 13 to revolve to the position shown in Fig. 3, at which position a further outward movement of the parts is prevented; it being noted that the ends of the pins 22 will ride into the spaces extant between the edges 26 of the track-members and the edges of the abutments 25. In such position a swinging movement of the dead-bolt is prevented, incident to its engagement with the keeper. A retraction of the rotatable bolts is precluded, in that the heads thereof will engage with the keeper flange if forcible retraction is attempted. If, now, the movement of the parts is reversed, i. e., a pull is exerted upon the dead-bolt, it will be apparent that the shafts 13 cannot move longitudinally of the lock case for the reason that the pins, in engagement with the edges 26 of the track-members, will prevent this occurrence. However, the dead-bolt will move rearwardly to the position shown in Fig. 2, and the pins 22 in cooperation with the edges of the slots 23, will cause the shafts 13 to rotate axially to the position also shown in this figure; in which the inner pin ends clear the edges 26 of the track-members and the bolt heads will clear the keeper flanges if retracted. Thereupon, the bolt assembly may be wholly retracted from within the lock case to the position shown in Fig. 1.

With a view properly to connect the plate 15 with the crank-member, it will be observed in the embodiment illustrated—reference being had particularly to Fig. 5—that the pin 18 has a head 27 at its outer end, the pin-portion riding between the arms of the crank 19, and the head engaging the inner faces of these arms to prevent accidental detachment. The pin is continued in the form of a boss or stud 28 having at its outer end a U-shaped recess 29 which is intended for engagement with the extension of a crank operated by a key (not shown). The stud 28 has a transverse bore, within which a tube 30 is mounted, these elements frictionally contacting normally to prevent relative movement thereof. The lower end of the tube is inturned as at 31, and the upper end thereof is outturned as at 32, the latter providing a flange which engages the upper face of the stud to limit the projection of the tube. A rod 33 extends within the tube and beyond the ends of the same and has reduced end-ports 34, which extend within notches 35 formed in the flanges 16 of the plate 15. A spring 36 is coiled about the rod 33 and has

one of its ends pressing against the inner face of the upper flange 16, its opposite end pressing against the inner face of the inturned flange 31 of the tube 30. As a consequence, the stud 28 is normally pressed downwardly, the entire assembly being supported properly upon the rod 33 mounted by the plate 15. Thus, when the crank is in the position shown in Fig. 1 it will not move accidentally from such position, and, on the other hand, it cannot move beyond such position, in that the stop pin 37 mounted by the case will prevent this. Obviously, as the crank is swung the spring 36 will be compressed, and upon reaching a position beyond dead center, the spring will fully project the bolt assembly.

This connecting and actuating device is preferably applied to the plate 15 prior to the introduction of the latter in the crank case. Such application is accomplished simply by taking the device as a unit, inserting the head 27 through the enlarged portion of the keyhole slot 17, and then forcing the stud 28 upwardly until the parts assume the position shown in Fig. 5, in which position the head cannot register with the enlarged portion of the slot, and, consequently, with the reduced end-ports 34 of the rod 33 within the notches 35 the device cannot become accidentally removed from the plate. The dead-bolt and plate are now placed within the lock case, care being taken that the pin 18 be disposed between the arms of the crank 19. Thereafter, the rotatable bolts are introduced into the bores of the dead-bolt 11, and the pins 22 are dropped into place. Obviously, upon the cover plate (not shown) being applied, the parts cannot of themselves become disassembled, and it will be understood that the foregoing operations may be accomplished with minimum effort, time and skilled labor.

Thus, among others, the objects of this invention have been accomplished, and since certain changes may be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A lock, including, in combination, a case, a carrier movable within said case, a bolt rotatably supported by said carrier, and a single means associated with said bolt and co-

operating with said carrier and case to effect a rotation of said bolt and limit the projection thereof.

2. A lock, including, in combination, a case, a carrier within said case, means for projecting and retracting said carrier, the latter being formed with a bore, a bolt rotatably supported within said bore, said carrier being formed with a groove extending at a tangent to the direction of travel thereof, and a pin supported by said bolt and extending within said groove whereby upon the bolt and carrier moving with respect to each other said bolt will rotate, said pin cooperating with said case to limit the movement of said bolt with said carrier.

3. A lock, including, in combination, a case, a carrier, means for projecting and retracting said carrier, a bolt rotatably supported by said carrier, a pin removably carried by said bolt and cooperating with said carrier to cause a rotation of said bolt when the latter and carrier are moved with respect to each other, said pin cooperating with said case to effect such movement.

4. A lock, including, in combination, a dead-bolt formed with bores, rotatable bolts supported within said bores, a lock case normally housing said bolts, said carrier being formed with slots extending through to said bores and at tangents to the direction of travel of the dead-bolt, and pins removably associated one with each of said rotatable bolts and riding within said slots to effect a rotation of said bolts when the latter are axially shifted with respect to the dead-bolt, and means cooperating with said pins to effect such shifting.

5. A lock, including, in combination, a carrier formed with a bore and a tangentially-extending slot, means for projecting and retracting said carrier, a bolt rotatably mounted within said bore, a pin extending through

said bolt and engaging said slot whereby upon said bolt and carrier being shifted with respect to each other rotation of the former will result, a lock case for said carrier and bolt, and means forming a part of said case and also engaging said pin to effect such shifting.

6. A lock, including, in combination, a bolt, a carrier therefor, a crank, a pin secured to said crank, a rod extending across said carrier, said pin being slidably connected with said rod whereby upon said crank being turned said carrier and bolt will be projected or retracted.

7. A lock, including, in combination, a bolt, a carrier therefor, a crank, a pin secured to said crank, forked portions forming a part of said carrier, a rod having its ends extending into said forked portions and said pin being slidably connected with said rod.

8. A lock, including, in combination, a bolt, a carrier therefor, a crank, a pin secured to said crank, a rod extending across said carrier, said pin being slidably connected with said rod whereby upon said crank being turned said carrier and bolt will be projected or retracted, and a spring associated with said rod and cooperating with said pin to normally urge the same in one direction.

9. A lock, including, in combination, a bolt, a carrier therefor, a crank, a pin secured to said crank, a rod extending across said carrier, said pin being slidably connected with said rod whereby upon said crank being turned said carrier and bolt will be projected or retracted, an enlarged head formed on said pin and said carrier being formed with a key-hole slot, the reduced portion of which slidably accommodates said pin, the enlarged portion thereof being of a dimension adequate for the passage of the head thereof.

In testimony whereof I affix my signature.
SAMUEL SEGAL.
